TROUSER GUARD MACHINE

Lawrence A. Moore, Elkhart, Ind., assignor to
 American Coating Mills, Inc., Elkhart, Ind., a
 corporation of Indiana

Application September 23, 1940, Serial No. 357,847

12 Claims. (CL 93—1)

This invention relates to machines for producing articles from strip material, and has to do with a machine in which the strip material, after being cut into suitable blanks, is subjected to a forming operation whereby the blanks are formed into the desired articles.

My invention is directed to a machine of the character stated having means whereby the strip material may be supported in the form of a roll, from which the material is passed through the machine, in which it is cut to proper widths and lengths to provide blanks of proper size and shape, these blanks being then passed through forming means and thereby formed to desired shape.

This invention is also directed to means permitting proper rotation of the roll as the strip material is withdrawn therefrom, while effectively preventing over-running of the roll, the provision of means whereby the strip material may be printed upon or not as desired, the provision of means for slitting the strip lengthwise into desired widths, such slitting means being adjustable whereby the machine is suitable for handling strip material of various widths, and the provision of improved cutting means for cutting the strip material into desired lengths to provide the blanks. In conjunction with the adjustable slitting means, I also provide adjustable guide means for the strip material during passage thereof through the machine, whereby strip material of various widths may be accommodated. I also provide means whereby the machine may operate upon the strip material continuously in such manner that the strip material enters the machine at one end and the desired articles are delivered at the other end of the machine, or, alternatively, the slitting and cutting and associated mechanisms may be disabled and previously cut blanks may be delivered one at a time to the forming section of the machine to be formed thereby to the desired articles. Further objects and advantages of my invention will appear from the detail description.

In the drawings:

Figures 1, 1A, 1B, and 1C, taken together, are a semi-diagrammatic lengthwise central vertical sectional view of a machine embodying my invention;

Figure 2 is a detail plan view of the printing unit drive shaft and the associated gear and clutch means;

Figure 3 is a plan view of the means for supporting the roll of strip material and for retarding rotation thereof and associated parts;

Figure 4 is a side view, partly broken away, of the supporting and retarding means, and associated parts, of Figure 3;

Figure 5 is a sectional view, on an enlarged scale and partly broken away, taken substantially on line 5—5 of Figure 1, of the guide means leading to the printing unit;

Figure 6 is a plan view of the guide means of Figure 5;

Figure 7 is a sectional view, on an enlarged scale and partly broken away, taken substantially on line 7—7 of Figure 1, of guide means leading from the printing unit;

Figure 8 is a sectional view, on an enlarged scale and with certain parts shown in elevation, taken substantially on line 8—8 of Figure 1, of the first set of deckle slitting rolls and associated parts;

Figure 9 is a sectional view, on an enlarged scale and with certain parts shown in elevation, taken substantially on line 9—9 of Figure 1, of the guide means leading to the measuring rolls;

Figure 10 is a sectional view, on an enlarged scale and with certain parts shown in elevation, taken substantially on line 10—10 of Figure 1A, of the guide means leading to the cutting rolls;

Figure 11 is a plan view of the guide means of Figure 10;

Figure 12 is a side view, partly broken away, of the gears at one end of the cutting rolls;

Figure 13 is a side view, partly broken away, of the rails at one end of the cutting rolls;

Figure 14 is an isometric view of one of the die blocks and the cutting dies and associated parts carried thereby;

Figure 15 is a detail plan view of the main clutch and associated parts;

Figure 16 is a plan view, partly broken away, of the guide means leading from the cutting rolls to the pulling rolls;

Figure 17 is a sectional view of the guide means of Figure 16, taken substantially on line 17—17 of Figure 1A and on an enlarged scale;

Figure 18 is a sectional view, on an enlarged scale, taken substantially on line 18—18 of Figure 1A, of the guide means leading from the pulling rolls to the transfer unit;

Figure 19 is a sectional view, on an enlarged scale, taken substantially on line 19—19 of Figure 1B, of the transfer belt guide means;

Figure 20 is a plan view, partly broken away, of the guide means of Figure 19;

Figure 21 is a sectional view, on an enlarged scale, taken substantially on line 21—21 of Figure 1B, of the transfer belt guide means at the

portion thereof leading from the transfer belts to the forming rolls;

Figure 22 is a plan view, partly broken away, of the guide means of Figure 21;

Figure 23 is a sectional view, partly broken away and on an enlarged scale, taken substantially on line 23-23 of Figure 1B;

Figure 24 is a plan view of a trouser guard blank produced by the machine of my invention;

Figure 25 is an isometric view of a conventional type of coat hanger with a trouser guard formed from the blank of Figure 24 applied thereto;

Figure 26 is a sectional view, on an enlarged scale, taken substantially on line 26-26 of Figure 25;

Figure 27 is a semi-diagrammatic sectional view of the forward portion of the forming section of the machine, on the order of Figure 1B but with the hopper for delivering cut blanks from stacks to the forming rolls applied and the transfer unit removed;

Figure 28 is a sectional view, on the order of Figure 21, of the stack feed hopper of Figure 27;

Figure 29 is a diagrammatic view of the drive for the feed rollers of the stack feed hopper;

Figures 30 and 30A, taken together, are a diagrammatic plan view of the drive system of the machine; and

Figures 31 and 31A, taken together, are a diagrammatic side view of the drive system of the machine.

The machine, in the form thereof intended for continuous operation on strip material, comprises a slitting and cutting section, including a printing unit which may be used or not as desired, a transfer unit, and a forming section in which the blanks, delivered from the trimming and slitting and cutting section to the forming section, are formed into desired shape. The transfer unit is removable and replaceable by a feed hopper unit for delivering previously cut blanks from stacks to the forming section, means being provided for disabling the cutting and slitting and trimming sections when the stack feed hopper is used, thus providing an alternative form of the machine.

The machine, as a whole, comprises a suitably constructed main frame 35 supported by appropriately located base frames 36, 37, 38, and 39, which base frames may be enclosed in a suitable manner to provide housings available for storage or other purposes. A frame 40 is provided at the front of main frame 35 spaced a short distance therefrom. Suitable means, to be described more fully later, is provided for rotatably mounting on frame 40 a roll 41 of strip cardboard or analogous material. A substantially elongated U-shaped frame 42 is secured at its lower end on a rod 43 rockably mounted at the upper rear portion of frame 40. A straightening roll 44 is rotatably mounted at the upper end of frame 42, which extends upward and forward from rod 43, and bears upon the circumferential surface of roll 41, with strip 45 passing from roll 41 about the forward portion of roll 44 and over the latter, it being noted that frame 42 is yieldingly urged, by means to be later described, in a clockwise direction about the axis of rod 43 so as to cause movement of straightening roll 44 downward and inward toward the axis of strip roll 41, as the latter is reduced in diameter by the withdrawal of strip 45 therefrom. Straightening roll 44 assures that the strip 45 will be delivered from roll 41 to the first section of the machine

in a straight and true condition, in a manner to be described presently.

The strip 45 passing from straightening roll 44 into the first section of the machine is maintained under appropriate tension, as will appear more fully hereinafter. A tell-tale roll 46, mounted in a frame 47 pivoted on the upper portion of frame 42, bears upon the upper face of strip 45 in rear of and adjacent roll 44. A rod 48, connected at its upper end to frame 47 and slideable through a guide finger 49 secured to frame 42, is disposed to actuate a switch 50, of known type, and suitably mounted on frame 42, upon downward movement of tell-tale roll 46 due to breaking of the strip 45. A cam member 51, carried either by rod 43 or by frame 42 and movable with the latter, is disposed to actuate a switch 52, similar to switch 50 and suitably mounted on frame 40, when straightening roll 44 has moved inward of strip roll 41, due to reduction in size of the latter in the withdrawal of the strip therefrom, a predetermined distance, as into the position indicated by the dot and dash lines in Figure 1. The switches 50 and 52, when actuated in the manner stated, may cause operation of known signals (not shown), suitably located, thereby apprising the operator of the machine when either the strip 45 has broken or the strip roll 41 is nearing its end and should be replaced.

An arm 53 (Figures 3 and 4) is secured upon rod 43 adjacent one end thereof and extends upward therefrom. A tension spring 54 is anchored at one end to arm 53, the other end of this spring being anchored to frame 40. Spring 54 provides yielding means for urging the straightening roll 44 downward and inward toward the center of strip roll 41, frame 42 being secured to rod 43 for movement therewith. Strip roll 41 is secured, in a suitable known manner, upon a central stub shaft 55 rotatably mounted in open top bearing blocks 56 secured to frame 40. Shaft 55 has a pin 57 secured through one end thereof for engagement in bayonet slots, one of which is shown at 58, in a head 59, secured to a shaft 60 disposed in alignment with the bearing blocks 56 and stub shaft 55. Shaft 60 is rotatably mounted in bearing blocks 61 suitably secured to frame 40 and is confined against endwise movement. A brake drum 62 is secured upon shaft 60 for cooperation with a brake band 63, of leather or other suitable material. Band 63 is anchored at one end, at 64, to frame 40, and is passed about drum 62 in the manner shown in Figure 4, the other end of band 63 being connected by a tension spring 65 to arm 53.

When the strip roll 41 is full, or substantially so, and but little of strip 45 has been withdrawn from this roll, the straightening roll 44 is in the position shown in Figures 1 and 4 and spring 65 is under maximum tension, brake band 63 and drum 62 then cooperating to exert maximum braking or retarding effect, resisting rotation of the strip roll 41 as the strip 45 is withdrawn therefrom. That assures proper tensioning of strip 45 as it is withdrawn from roll 41 and also prevents over-running of the latter due to inertia, such as might occur if roll 41 were permitted to rotate freely during withdrawal of the strip 45 therefrom. As roll 41 is reduced in size, in the withdrawal of strip 45 therefrom, straightening roll 44 moves inward toward the center of strip roll 41 and the tension of spring 65 is correspondingly reduced, thus progressively

reducing the braking effect of brake band 63 and drum 62. That automatically compensates for reduction in size of roll 41, permitting the latter to rotate at proper speed at all times, while assuring proper tensioning of strip 45 and eliminating possibility of over-running of the strip roll. Arm 53 is provided with a series of spaced openings for attachment of the tension springs 54 and 55, whereby the tension of these springs, within limits, may be varied as required. Any other suitable means for adjusting the tension of the springs may be provided.

A housing 66 (Figure 1) is removably mounted in a suitable known manner at the front of frame 35. This housing 66 contains a cleaning assembly comprising brushes 67 and 68, mounted on shafts 69 and 70, respectively, and a fan 71 mounted on a shaft 72, there being an exhaust opening (not shown) through one side of housing 66 for fan 71. Housing 66 is provided, in its front wall, with an entrance opening or slot 73 and, at the lower edge of this opening, with arcuate plates 74 over which strip 45 passes to slot 73. The strip 45 passes from slot 73 between the brushes 67 and 68 and then through slot 75 in the back wall of housing 66 to guide 76, shown more clearly in Figures 5 and 6. Each of the guides comprises an angle member 77 to the inner face of the vertical arm of which is secured a strip 78 spaced from horizontal arm 79 of member 77 and defining therewith a passage 80 for the edge portions of strip 45. The horizontal arm 79 of angle member 77 seats upon the upper flange 81 of an angle cross member 82 of printing unit 83, which is removably mounted in frame 35 in a suitable manner. Arm 79 of each of the angle members 77 has secured thereto a depending stud 85 extending through a lengthwise slot 86 in arm or flange 81 of cross member 82. Each member 77 also has an outwardly projecting ear 87 welded or otherwise suitably secured thereto and seating upon arm 81 of cross member 82, ear 87 receiving a bolt 88, passing therethrough and through slot 86, with a nut 89 screwing upon the upper end of this bolt. The guide members 76 are thus mounted for adjustment toward and away from each other to accommodate various widths of strip material.

The printing unit 83 requires no extended description. It comprises an ink pan 92, a paddle 93 driven by shaft 94 and gearing 95, an ink roll 96, an ink transfer roll 97, a plate roll 98, and an impression roll 99, all of these rolls being geared together in a known manner. The printing unit is driven from shaft 100, through a pinion 101 on this shaft and a pinion 102 on a stub-shaft 103 parallel with shaft 100, pinion 102 meshing with pinion 101 and with gear 104 secured on the shaft of plate roll 98. Pinion 101 is disposed at the inner face of a disc 105 secured on shaft 100. A removable pin 106 is insertable through disc 105 and into a corresponding bore or recess in pinion 101, for coupling the latter to shaft 100 to be driven thereby. Pinion 101 is otherwise free from shaft 100 and, by withdrawing the pin 106, may be disconnected from shaft 100 which may then continue to rotate without driving the printing unit. In that manner the printing unit may be enabled and disabled as required, for a purpose which will later appear. Any other suitable means may be provided for coupling and uncoupling the pinion 101 to and from the shaft 100.

From the printing unit 83 the strip 45 is led rearward beneath and about an idling guide roller 109, from which it passes forward through guides 110, shown more clearly in Figure 7. Guides 110 conveniently are formed of sheet metal, are of elongated U-shape in cross section, and are disposed with their open ends inward. Each of the guides 110 has secured thereto a supporting block 111 through which passes a supporting cross rod 112 upon which block 111 is adjustably secured by a set screw 113. Guides 110 are thus mounted for adjustment toward and away from each other to accommodate various widths of strip material.

From guides 110 strip 45 passes forward beneath a second idling guide roller 115 disposed above the printing unit 83, as shown in Figure 1, strip 45 passing forwardly and upwardly about roller 115 and from the top of this roller through guides 116, it being noted that the top of roller 115 is disposed substantially in the plane of the passages of guides 116 so that the strip may be led directly from roller 115 to guides 116.

From the guides 116 the strip passes through the first set of deckle slitting rolls, shown more clearly in Figure 8. This set of rolls comprises a pair of lower rolls 117 cooperating with a pair of upper rolls 118. Each of the rolls 117 and 118 is provided, at one face thereof, with radially disposed V-shaped teeth 119 and is disposed in overlapping relation to a corresponding upper or lower roll, thus providing a pair of rolls 117 and 118, the teeth 119 of which are in overlapping meshing relation, with the teeth of the upper roll 118 directed oppositely to the teeth of the lower roll 117, as shown in Figure 8. Each of the lower rolls 117 is adjustably secured, by a set screw 120, on a shaft 122 rotatably mounted in bearing blocks 123 suitably secured to angle members 124 of the main frame 35. Each of the upper rolls 118 is adjustably secured, by means of a set screw 125, on a shaft 126 rotatably mounted in bearing blocks 127 slideable on vertical columns 128 bolted to bearing blocks 123. Shaft 122 is confined against endwise movement by collars 129 suitably secured thereon. Shaft 126 is likewise confined against endwise movement by collars 130 and is provided, at one end, with a knob 131 secured thereon for rotating shaft 126 and with it the upper deckle slitting rolls 118 in threading the strip 45 through this set of slitting rolls.

A screw stud 132 is secured, as by welding, to each of the bearing blocks 127 and is slideable through a cap plate 133 secured to the upper ends of the standards 128 upon which bearing block 127 slides. Nuts 134 are threaded upon stud 132, at the upper and the lower faces of cap plate 133, and provide therewith means for adjusting bearing blocks 127 on the standards 128. The adjusting means referred to renders it possible to raise the upper rolls 118 sufficiently to clear the lower rolls 117 thus rendering this set of slitting rolls inoperative, the strip 45 then passing over lower rolls 117 without being operated on thereby. It also will be apparent that the rolls 117 and the rolls 118 may be adjusted upon the shafts 122 and 126, respectively, so as to vary the spacing of the rolls of each pair for accommodating different widths of strip material, as will be further explained presently.

A housing 135 (Figure 1), open at its front, is mounted at the front of frame 35 above housing 66. Housing 135 is provided with an en-

trance opening or slot 136 in its rearward wall and with an arcuate plate 137 leading upward and inward to the lower edge of slot 136. The latter slot has its lower edge disposed substantially in the plane of the top of guide roll 115 and in the plane of the passage of guide means 116, as will be clear from Figure 1. The strip material 45 may thus be led from roll 41 either to the printing unit and thence to guide means 116 and the first set of deckle slitting rolls, or it may be led, by means of housing 135, directly to guide means 116, above guide roll 115, and thence to the first set of deckle slitting rolls.

From the first set of deckle slitting rolls strip 45 passes through guide means 140 to a second set of deckle slitting rolls comprising a pair of upper rolls 141 and a cooperating pair of lower rolls 142. The second set of deckle slitting rolls is similar in construction and operation to the first set of deckle rolls shown in Figure 8 and requires no further description.

From the second set of deckle slitting rolls strip 45 passes through guide means 143. Guide means 116 and guide means 140 are similar to the guide means 76 shown in Figures 5 and 6 and above described in detail, and require no further description, it being noted that the guide rollers 109 and 115 are of adequate length to handle the widest strip material which it is contemplated passing through the machine, and the guide means comprising the members 110, the guide means 116 and the guide means 140 are all adjustable to accommodate various widths of strip.

The guide means 143 is shown more clearly in Figure 9. It comprises two angle members 144, each provided, at the inner face of its vertical arm, with a strip 145 disposed above horizontal arm 146 and defining therewith a passage 147 for the edge portion of strip 45. A screw stud 148, secured in arm 146, passes through a lengthwise slot 149 in an angle supporting cross member 150, this stud receiving nut 151 for securing member 144 in adjustment. A bracket 152, of elongated inverted U-shape, is secured to the upper face of cross member 150 and overlies slots 149 therein. This bracket 152 carries a guide strip 153 spaced above a strip 154 secured to member 150, the strips 153 and 154 defining therebetween a passage 155 disposed midway between the angle member 144 and in the plane of passages 147 thereof. It will thus be seen that the guide means 143 also is adjustable for accommodating strip material of various widths that pass through the machine.

From guide means 143 the strip 45 passes between upper and lower measuring rolls 156 and 157 secured on shafts 158 and 159. The measuring rolls are mounted in substantially the same manner as the deckle slitting rolls and a brief description thereof will suffice. Shaft 158 is rotatably mounted, adjacent each end, in a bearing block 160 to which is secured a screw stud 161 slidable through a cap plate 162, this stud receiving a coil compression spring 163 confined between bearing block 160 and cap plate 162. A nut 164 screws upon stud 161 and bears on the upper face of cap plate 162. Roll 156 is thus yieldingly urged toward roll 157 for gripping between these two rolls the strip 45, and the upper roll 156 may be adjusted vertically as desired, the nuts 164 providing positive stops limiting downward movement of the upper roll. Strip 45 passes from measuring rolls 156 and 157 beneath a rubber covered wetting roll 165 and from

the latter over an idler guide roll 166a, as will be clear from Figure 1. Wetting roll 165 is in contact with a water roll 166 secured on a rotatably mounted shaft 167, roll 166 operating in a water pan 168 to which water is supplied so as to be maintained at a constant level therein, in a known manner. Wiper means 170 contacts the upper portion of water roll 166 for determining the amount of water delivered thereby to the wetting roll 165. The latter roll serves to moisten the strip 45 to proper extent for further treatment.

Shaft 167 of water roll 166 is driven from shaft 159 of the lower measuring roll 157 by a chain 172 (Figures 30 and 31) passing about sprockets 173 and 174 secured on shafts 159 and 167, respectively. Meshing pinions 175 and 176 are secured on shafts 158 and 159, respectively, whereby these shafts are driven at the same speed and in opposite directions. A sprocket 177, secured on shaft 159, is connected by a chain 178 to a sprocket 179, secured on shaft 100 for driving the printing unit. Gear 101, secured on shaft 100, meshes with pinion 102 secured on shaft 103, and pinion 102 meshes with gear 104 secured on shaft 98a of the plate roll 98 of the printing unit, in the manner previously stated. Gear 104 meshes with gear 178 secured on shaft 99a of impression roll 99, and with pinion 179 secured on shaft 97a of ink transfer roll 97, pinion 179 meshing with pinion 180 secured on shaft 96a of ink roll 96. A sprocket 181, secured on shaft 103, is connected by a chain 182 to a sprocket 183 secured on shaft 94 for driving the paddle 93 in the ink pan 92. A second sprocket 185, secured on shaft 103, is connected by a chain 186 to a sprocket 187 secured on a rotatably mounted countershaft 188. A gear 189, secured on countershaft 188, meshes with a gear 190 secured on the upper brush shaft 69, gear 190 meshing with a gear 191 secured on the lower brush shaft 70, and gear 191 meshing with a gear 192 secured on fan shaft 72. The water roll 166 and the printing unit and the cleaning mechanism, comprising the brushes 67 and 68 and the fan, are thus driven from shaft 159 of the lower measuring roll 157.

The measuring rolls 156 and 157 serve to withdraw the strip of cardboard or like material from roll 41 and to pull it through the printing unit or through the housing 135, as the case may be, and through the various guide means and the sets of deckle slitting rolls. In Figure 8 it is assumed that the strip 45 is originally of a width somewhat greater than twice the width of the desired blanks. Assuming that the articles to be produced are trouser guards, the strip 45 might be considered as somewhat greater than twice the width of a guard, that is, more than two guard widths. The first set of slitting rolls is adjusted to trim strip 45 to two guard widths, this trimming being effected by the teeth 119 of the deckle rolls, so as to provide deckle or serrated edges at the sides of the trimmed strip. One pair of the rolls of the second set of deckle slitting rolls is adjusted to slit strip 45 lengthwise thereof along its transverse center line thus separating it into two strips both edges of which are deckled or serrated, each strip thus produced being of the width of the desired blank from which the trouser guard is to be formed. The other pair of the second set of deckle rolls are not used at this time and, therefore, are adjusted along their shafts into inoperative position clear of the strip 45. The waste material trimmed off

of the lateral edge portions of the strip may fall downward in the machine adjacent and in rear of the printing unit. Suitably disposed guard plates may be provided for shielding the printing unit from dirt and dust as well as from the trimmings, such guard plates being known and not being shown. If the original width of strip 45 be more than three guard widths, the first set of deckle slitting rolls is adjusted to trim the sides of the strip, and the two pairs of rolls of the second set are adjusted to slit the strip lengthwise into guard widths, thus separating strip 45 transversely into three strips of equal width. In the event the original strip 45 is somewhat more than one guard width wide, either the first or the second set of deckle slitting rolls may be used for trimming the strip to guard width, the upper rolls of the set not used being raised to inoperative position in the manner previously described. If desired, the strip 45, before winding it into the roll 41, may be trimmed with deckle edges to a width equal to one, two or three guard widths. If the pretrimmed strip 45 is of one guard width both sets of the deckle slitting rolls may be disabled, in which case the trimmed strip will be passed through the machine without being operated upon by the deckle rolls. In the event the trimmed strip is of two guard widths, one pair of either set of the deckle rolls may be utilized for slitting this strip along its transverse center line, the other rolls of that set being disposed clear of the strip and the other set of rolls being disabled. When the trimmed strip 45 is of three guard widths either set of deckle rolls may be used for slitting this strip into three equal widths, the other set of rolls being disabled. It will thus be seen that by proper adjustment of the deckle slitting rolls a strip 45 of cardboard or other suitable material having a width of from one to three times the width of the desired blanks, or greater, may be handled with expedition and facility.

The printing unit 83 is supported by a suitable frame in the main frame 35, as will be clear from Figure 1, and may be removed and replaced as a unit, as may be necessary or desired. It will also be noted that the guide roller 115, the deckle slitting rolls, the measuring rolls and the water roll and wetting roll, and associated parts, are mounted on a suitable frame removably supported in the main frame 35 so as to be removed therefrom and replaced therein as may become necessary.

From guide roll 166a strip 45 passes between two cleaning brush rolls 195 and 196 secured on shafts 197 and 198, respectively, rotatably mounted in a bracket 199 secured to cross beam 200 of main frame 35. From the rear brush roll 196 strip 45 passes beneath a guide roll 201 secured on a rotatably mounted shaft 202 on which is also secured a sprocket 203 (Figures 30 and 31). A chain 204 passes about sprocket 203 and from the latter over the upper portion of a sprocket 205 secured on shaft 198, and thence about a sprocket 206 secured on shaft 197. The brush rolls 195 and 196 are thus driven in opposite directions, from shaft 202.

Strip 45 passes from guide roll 201 to guide means 210, shown more clearly in Figures 10 and 11. This guide means comprises three pairs of angle members 211, the members of each pair being disposed in opposed relation with their upper arms horizontal and having guide strips 212 secured to the inner faces of their vertical arms and spaced from their upper arms to define

therewith passages 213 for the side edge portions of a strip cut from strip 45. In that connection, it will be recalled that the strip 45 is trimmed to proper width, if wider than one guard width, and is slit lengthwise, by the deckle slitting rolls, to provide two or three, as the case may be, strips each of one guard width. Assuming that strip 45 has been slit lengthwise to provide three strips, the latter strips will spread apart or fan out from guide roller 166a to guide roll 201, each pair of the angle members 211 receiving one of the three strips, the edge portions thereof entering and passing through the passages 213. Each of the angle members 211 has a post 215 welded to its upper horizontal arm, these posts receiving a connecting rod 216 to which they are adjustably secured by set screws 217. A post 218 is welded to the upper arm of one angle member 211 of each pair, adjacent each end of such member. The posts 218 receive supporting rods 219 extending transversely of the main frame 35, set screws 220 being threaded into the upper ends of posts 218 for adjustably securing them upon rods 219. The guide members 211 of each pair are thus adjustable toward and away from each other to accommodate strips of different widths, and the pairs of guide members are adjustable toward and away from each other for accurately positioning the strips with respect to cutting means for severing the strips into blanks, as will be described presently.

Upper and lower rubber covered pulling rolls 222 and 223, respectively, secured on shafts 224 and 225, extend between each pair of guide members 211, as in Figure 1A. Shaft 225 of the lower roll 223 is in the form of a stud shaft rotatably mounted in an arm 226 pivoted on a cross rod 227 mounted in brackets 228 depending from a frame 229, in which frame shaft 224 is rotatably mounted. An elongated U-shaped angle bracket 230, secured to and depending from frame 229, extends transversely of main frame 35. An eye bolt 231, pivoted at its upper end to arm 226, is slidable through the bight portion of bracket 230 and is provided with a coil compression spring 233, mounted thereabout which is confined between nut 232 and the bight portion of bracket 230, this spring yieldingly urging roll 223 upward toward roll 222. The nut 232 is adjustable upon bolt 231 for controlling compression of spring 233. Roll 222 is driven at somewhat higher speed than the measuring rolls 156 and 157, so as to maintain the strips pulled thereby through the guide means 210 under desirable tension, the yielding mounting of roll 223 permitting slippage sufficient to prevent tearing or breaking of the strip gripped between the rolls 222 and 223. It will be understood that each pair of the angle guide members 211 has associated therewith a pair of pulling rolls 222 and 223, though but one pair of such rolls has been shown for purposes of illustration.

The strips into which strip 45 has been separated pass from the guide means 210 between a pair of cutting rolls comprising an upper plate roll 235 and a lower die roll 236. Plate roll 235 is secured on a shaft 237 rotatably mounted in bearing blocks 238 constituting the side members of a rectangular frame 239 depending from two I-beams, one of which is shown at 240. Bearing blocks 238 are bolted or otherwise suitably secured to I-beams 240, and the latter seat upon cross I-beams 200 and 241 of the main frame 35.

A bearing block 242 is secured to and depends from each of the bearing blocks 238, and a spacer 243 is secured to the underface of each bearing block 242, frame 229, formed in two sections, being suitably secured to bearing blocks 242 and spacers 243. The parts referred to may be secured together as by bolting or any other suitable manner and the frame 229 provides a support for the cross rods 219 and related parts, for the guide means 210.

Die rolls 236 is secured on a shaft 245 rotatably mounted adjacent each end in a bearing block 246 slidable on guide rods 247 secured to and depending from bearing block 238. Rods 247 have their lower portions 247a reduced in diameter and are threaded at their lower ends for reception of nuts 248 which bear against the underface of a cross bar 249 slidable on the rods. A coil compression spring 250 is mounted about a plunger rod 251 disposed between rods 247 and slidable through cross bar 249 and an upper guide plate 252 suitably secured on rods 247. The upper end of plunger rod 251 bears against the underface of bearing block 246 and spring 250 is confined between cross bar 249 and a collar 253 on plunger rod 251. Die roll 236 is thus provided with a floating mounting at each end and is yieldingly urged upward toward the plate roll 235 in an obvious manner. By means of the nuts 248 the compression of spring 250 may be varied to suit requirements.

Die roll 236 has mounted therein, in a suitable known manner, two diametrically opposite die blocks 255, the outer faces of which are flat. Each block 255 carries three cutting dies 256 (Figure 14) projecting beyond the outer face of blocks 255 and shaped as shown. Each of the dies 256 comprises a leading portion and a following portion, both of the same configuration, the following portion being provided with a resilient pad 257 formed of sponge rubber or other suitable material, this pad fitting into and about the following portion of the die with its upper surface disposed, normally, somewhat above the cutting edges of the following portion of the die, for a purpose to be explained presently.

A gear 258 (Figures 12 and 30) is secured on shaft 237 adjacent each end of plate roll 235 and a bearing disc or rail 259 is secured to the ends of plate roll 235. The gears 258 mesh with gears 260 secured on shaft 245 of die roll 236 adjacent each end thereof, one of such gears 260 being shown in Figure 12. A bearing disc or rail 261 is secured to the ends of die roll 236 and is maintained in bearing contact with the circumferential surface of the corresponding rail 259 on shaft 237 by the compression spring 250 in an obvious manner. The rails 259 are of circular shape throughout their extent, the pitch circle of the respective gears 258 corresponding to the contour of the associated rails 259. Each of the rails 261 is provided with two flat areas 261a corresponding to the flat outer faces of the die blocks 255. The pitch contour of the teeth of each of the gears 260 corresponds to the contour of the adjacent rail 261, this gear accordingly having two flat areas corresponding to areas 261a of rail 261. Plate roll 235 has mounted thereon, in any suitable known manner, two diametrically opposite cutting plates 262 conforming in curvature to roll 235, the outer faces of these plates being flush with the outer circumferential faces of the rails 259, as shown more clearly in Figures 1A and 13.

Gears 258 mesh with pinions 265 secured on a countershaft 266 rotatably mounted parallel with shaft 237. Countershaft 266 is driven from a rotatably mounted shaft 267, by means of a sprocket 268 loose on the latter shaft and optionally clutched thereto and declutched therefrom by clutch means 269, which will be described more fully later, sprocket 268 being connected by a chain 270 to a sprocket 271 secured on countershaft 266 adjacent one end thereof. Gears 258, and with them rails 259 and plate roll 235, are driven in clockwise direction, as viewed in Figure 12, and serve to drive gears 260, and with them rails 261 and die roll 236, 15 in counterclockwise direction. The guide means 210 directs the strips into which strip 45 has been slit, between the rolls 235 and 236 and to position them accurately for cutting by the dies 256. In the rotation of the cutting rolls, the strips are cut into suitable lengths to provide blanks b, one of which is shown in Figure 24, 20 each of these blanks having serrated or deckle side edges, as shown, and having each end more or less rounded and provided with a substantially hook-shaped slit c, there being a short central slit c¹ extending from the inner hook portion of one of the slits c, produced by a corresponding extension of the following portion of cutting die 256, as will be clear from Figure 25 14.

The blanks b pass from the cutting rolls to blank guide means 275 shown more clearly in Figures 16 and 17. The guide means 275 comprises a plurality of spaced parallel guide strips 276 secured to upper and lower angle cross members 277 which are suitably secured to frame 229. Cross bars 278 are suitably secured, as by means of screws 279, to the upper strip 276. Posts 280 are secured to cross bars 278 and extend downward therefrom and at the sides of strips 276, the latter being disposed midway between adjacent posts. The posts and the strips thus define passages for the blanks b, which passages are of somewhat greater width than the blanks.

The blanks pass from the guide means 275 between three pairs of pulling rolls, one pair for each passage. Each pair of pulling rolls comprises an upper roll 282 (Figure 1A) and a co-operating lower roll 283. The rolls 282 and 283 are rubber covered for gripping between them the blanks b, and roll 283 is mounted on a stud 284 carried by an arm 285 pivoted on a cross rod 286 mounted in an angle iron bracket 287 secured to frame 229. Arm 285 is yieldingly urged upward by a coil compression spring 288 mounted about an eye bolt 289, slidable through bracket 287 in the same manner as slip roll 223 is urged upward. The upper pulling roll 282 is secured on a shaft 290 rotatably mounted in frame 229. A sprocket 291, secured on shaft 290, is connected by a chain 292 to a sprocket 293 secured on shaft 224 of the upper slip roll 222. A pinion 294 is secured on shaft 224 and meshes with a pinion 295 secured on a countershaft 296 rotatably mounted in bearing blocks 242 parallel with shaft 224. Pinion 295 meshes with gear 258 secured on shaft 237 of the plate roll 235. The pinions 294 and 295 are of equal diameter, as are the sprockets 291 and 293. The upper pulling roll 282 is, accordingly, driven at the same speed as the upper slip roll 222.

The pulling rolls 282 and 283 are so disposed relative to the cutting rolls that the rearward or leading portion of strip 45 enters between the

pulling roll shortly before severing of the strip by the cutting rolls to produce a blank *b*. Since the lower pulling roll 283 is yieldingly urged upward, a certain amount of slippage is permitted at that time to prevent tearing of the strip while maintaining it under desirable tension. Shortly thereafter the strip is severed by the cutting rolls, the dies cutting the following end of the blank gripped by the pulling rolls and the leading end of the next succeeding blank. The blank thus severed from the strip is then advanced at increased speed by the pulling rolls 282 and 283, so that the cut blanks are thus spaced a short distance apart. As previously mentioned, the following portion of die 256 (Figure 14) has associated therewith an elastic cushion 257. As the dies and the plates of the cutting rolls come into register, plate 262 rolls across the dies, which are urged toward the plate by spring pressure in the manner previously described, roll 236 moving upward abruptly so as to, in effect, strike the strip 45 a sharp blow with the die. This assures clean and accurate cutting of the strip. Since the forward portion of the strip is, at that time, gripped between the pulling rolls 282 and 283, the following end of the blank thus produced will be pulled free of the cutting rolls. In order to assure that the succeeding blank will enter the guide means 275 properly, it is desirable that means be provided to force out of the dies the end portion of the strip which is to be the leading end of the next succeeding blank. When this cut is made by the following portion of die 256, the cushion 257 is compressed and, as soon as the die 256 and the plate 262 pass out of cooperating relation, cushion 257 expands forcing the cut end portion of the strip out of the die, thus assuring that this end of the strip will clear the cutting rolls and pass into the guide means 275. In that manner the strip 45, or one of the strips resulting from slitting of the original strip 45, is cut into lengths to provide the blanks *b* and the latter are delivered in spaced apart relation, by the pulling rolls 282 and 283, to guide means 300, shown more clearly in Figure 18.

The guide means 300 is quite similar to the guide means 275. It comprises angle cross members 301 suitably secured to frame 229, and upper and lower guide strips 302 secured to cross members 301 and defining passages for the blanks *b*. The guide means 300 confines the blanks vertically but not horizontally, for a reason which will be explained presently.

The clutch means 269 is shown more in detail in Figure 15. It comprises a clutch member 305 fixed on shaft 267 and cooperating with a clutch member 306 loose on shaft 267, the latter clutch member carrying the sprocket 268. Clutch member 306 is moved toward and away from clutch member 305 by a clutch fork 307 pivoted at 308, to the forward end of which fork is pivoted one end of a link 309 the other end of which is pivoted to one end of a lever 310 pivoted at 311. An operating rod 312 is loosely connected, at 313, to the other end of lever 310 and extends therefrom outwardly beyond one side of the machine, being provided at its outer end with a suitable handle 314. That provides means for manually shifting clutch element 306 so as to clutch and declutch sprocket wheel 268 to and from shaft 267 as desired or necessary. A solenoid 315 is fixedly mounted on link 309 and is provided with a slidable core 316 urged outward into projected position by a coil compression

spring 317. When the machine is in proper operating condition, solenoid 315 is energized and core 316 is held in its retracted position. The solenoid 315 is suitably connected into a signal system including telltale or detector devices, such that if the strip 45 becomes broken or torn apart, or if the strip or the blanks jam in the machine, the solenoid circuit will be opened thus permitting of core 316 being moved into its projected position, indicated by dotted lines in Figure 15, by the compression spring 317. When in its projected position, core 316 is disposed to be engaged by a camming flange 320 secured to clutch member 305. Flange 320 shifts solenoid 315, and with it link 309, toward the left, as viewed in Figure 15, sufficiently to disengage clutch member 306 from clutch member 305 thus stopping the drive of sprocket 268 and of shaft 266. The latter shaft has two flywheels 321 (Figure 30) secured thereon at each end thereof, to carry the cutting rolls over the flats of the die roll rails, thus assuring smoother operation of the cutting rolls.

A sprocket wheel 325 (Figures 30 and 31) is secured on shaft 266, adjacent the other end thereof from sprocket 271. Sprocket 325 receives a chain 326 which passes over idler sprockets 327 and 328, about the upper portion of a second sprocket 329 secured on shaft 201, and then about a third sprocket 330 secured on shaft 159. A counter 331, of suitable known type, is driven, by means of a sprocket 332 and a chain 333, from a sprocket 334 secured on a stud 335 which is secured in one end of the shaft 231 of the plate roll 235. It will thus be seen that the first section of the machine, comprising the cleaning unit, the printing unit, the measuring rolls, the slitting rolls and the cutting rolls, and associated mechanisms, may be thrown into and out of operation by clutching and declutching sprocket 268 to shaft 267, either manually or automatically.

The blanks pass from the guide means 300 between the lower and upper rungs of upper and lower endless belts 340 and 341, respectively, of a transfer unit 342 extending between the rearward end of the first section of the machine, above described, and the forming section to be described presently. Unit 342 extends a short distance within the rearward end of the first section of the machine and is provided, at each side, with a bolting flange 343 seating upon and bolted to an angle cross member 344 of the main frame 35. At its rearward portion transfer unit 342 is provided, at each side thereof, with a bolting flange 345 (Figure 1B) seating upon and bolted to a flange 346 of main frame 35a of the rearward forming section of the machine. The rearward portions of the side walls of transfer unit 342 are of stepped formation, as indicated by dotted lines at 347, to fit correspondingly shaped portions of the forming section of the machine, for a purpose which will be explained more fully hereinafter. The transfer unit 342 may thus be removed and replaced as desired, in an obvious manner. Spacing bars 348 extend between the first section of the machine and the forming section, being bolted to the frames thereof, for maintaining proper spacing of these sections of the machine to assure proper positioning relative thereto of the transfer unit 342.

There are three pairs of belts 340 and 341, and these pairs of belts spread apart slightly or fan out rearwardly of the machine, as will be clear from Figure 30A. The upper belts 340 pass about

a driven roll 350 secured on a shaft 351 rotatably mounted in unit 342 adjacent the forward end thereof. At their rearward ends belts 340 pass about three pulleys 352 secured on a shaft 353 rotatably mounted in bearing members 354 of unit 342. At their forward ends belts 341 pass about a roll 356 secured on a shaft 357 rotatably mounted in unit 342, below and a short distance forward of shaft 351. The upper runs of belts 341 pass over idler pulleys 358 secured on a shaft 359 rotatably mounted in unit 342 transversely thereof. From the idler pulley 358 belts 341 pass rearward about idler pulleys 360 secured on a shaft 361 rotatably mounted in unit 342, parallel with and below and a short distance forward of shaft 353.

A pinion 365, secured on shaft 357, meshes with a pinion 366 secured on shaft 351, these two pinions being of equal diameter. A sprocket 367, secured on shaft 351, is connected by a chain 368 to a second sprocket 369 secured on shaft 290, from which the rolls 350 and 356 are driven at the same speed and in opposite directions, in an obvious manner. Preferably the rolls 350 and 356 and associated parts are enclosed within a housing 370 at the forward end of unit 342, this housing being provided with a suitable opening or slot 371 through which the guide means 300 extends. Since shaft 290 is driven by shaft 224, operation of the transfer unit is also controlled by the clutch means 269.

The belts 340 and 341 are arranged in pairs, each pair comprising an upper belt and a lower belt, so disposed that the blanks *b* will be gripped between the lower run of the upper belt and the upper run of the lower belt so as to be transported thereby. These runs of the belts operate, for the major portion of their length, in guide means 375, shown more clearly in Figures 19 and 20. This guide means comprises three pairs of opposed angle members 376 seating upon two pairs of angle cross members 377 of transfer unit 342. The angle cross members 377 are spaced apart to define between them a slot 378 through which extend screw studs 379 on which are threaded nuts 380. The angle members 376 are thus adjustable for accommodating blanks *b* of various widths and so as to assure accurate alignment of the blanks with the belts 340 and 341. Each pair of angle members 376 may also be adjusted transversely of unit 342, so as to be positioned accurately with respect to the pairs of belts and to the associated guide means, the guide means 275 being properly adjusted for directing the blanks through the guide means 300 to the respective belts 340 and 341.

The rearward portions of the belts 340 and 341, beyond the idler pulleys 358, operate in guide means 381 shown more clearly in Figures 21 and 22. This guide means comprises three pairs of angle members 382, the members of each pair being adjustably secured, adjacent each end, on a base plate 383, by means of screw 384 each of which may be threaded into any one of a series of tapped openings 385 in plate 383. The plates 383 seat upon two angle cross members 386 and 387 of unit 342, cross member 386 being disposed adjacent the forward end of guide means 381 and cross member 387 being disposed adjacent and slightly in rear of the idler pulleys 360. Each of the base plates 383 has secured therein a depending screw stud 388 which receives a nut 389 threaded thereon and a coil compression spring 390. Stud 388 of the rearward base plate 383 extends through a slot 391 in cross member

381, compression spring 390 being confined between the upper arm of cross member 381 and a washer 392 seating on nut 389. A plate 393 is welded or otherwise suitably secured to one of the angle members 382 of each pair and extends upwardly thereabove. Plate 393 is suitably bored and tapped to receive the threaded inner end portion of an adjusting rod 394, rotatably mounted through a bracket 395 suitably secured to one side of transfer unit 342 and extending upward therefrom. It will be understood that, in practice, there are three adjusting rods 394, one for each pair of angle members 382 which, together, constitute a guide and may be adjusted by means of rod 394 as a unit. At their rearward portions, beyond idler pulleys 352, angle members 382 have secured to the inner faces of their vertical arms guide strips 396 spaced from the lower arm of the respective angle members and defining therewith a passage 397 for the edge portions of the blanks *b*. The forward base plate 383 of each pair of angle members 382 has an angle bracket 400 welded or otherwise suitably secured to and extending from its under face, rearward of angle cross member 386. Bracket 400 receives the threaded inner portion of an adjusting rod 401 mounted for rotation through a side of unit 342 and confined against endwise movement in the same manner as rod 394. It will be understood that three adjusting rods 401 are provided. It will thus be seen that the pairs of angle guide members 382 may be adjusted at each end by the rods 394 and 401, to assure accurate positioning of these guide members relative to the guide means 375 and the belts 340 and 341, and to forming means, to be described presently, disposed immediately in rear of the guide means 381.

The forming means comprises an endless conveyor 405 formed of wooden blocks 406, the upper and lower runs of this conveyor traveling in guide rails 407 and 408, respectively, secured to main frame 35a of the former section of the machine. Blocks 406 are connected together by means of a sprocket chain 410 pivotally secured, by pintles 411 (Figure 23) to brackets 412 secured to the inner faces of the blocks. In their outer faces blocks 406 are provided with spaced parallel arcuate grooves 413 providing three arcuate channels extending lengthwise of conveyor 405. Chain 410 passes about a sprocket 415 (Figure 1B) secured on a shaft 416 rotatably mounted in frame 35a transversely thereof, adjacent and below the rearward end of the transfer unit 342. A second sprocket 418, secured on shaft 416, is connected by a chain 419 to a sprocket 420 secured on a countershaft 421 rotatably mounted in frame 35a, below and parallel with the idler pulley shaft 359. A second sprocket 422, secured on countershaft 421, is connected by a chain 423 to a sprocket 424 secured on shaft 267 (Figures 30, 30A, 31 and 31A). In that manner, shaft 267 is driven from shaft 416 carrying the conveyor sprocket 415, the latter sprocket being driven in counterclockwise direction as viewed in Figure 31A so that the upper run of the conveyor travels rearward.

The conveyor 405 may be of considerable length, its length being determined by requirements. At the rearward end of conveyor 405, chain 410 passes about a sprocket 426 secured on a shaft 421 rotatably mounted in frame 35a transversely thereof. It will be noted that sprocket 426 is disposed somewhat lower than guide rail 407 in Figure 1B, so that the rearward

portion of the upper run of the conveyor is inclined downward and rearward as shown. In like manner, sprocket 415 at the front of conveyor 405 is so disposed that the forward portion of the upper run of the conveyor is inclined downward and forward, as shown in Figure 1B.

A second sprocket 430, secured on shaft 427, is connected by a chain 431 to a sprocket 432 secured on a countershaft 433 rotatably mounted in frame 35a. A second sprocket 434 is secured on countershaft 433 and is connected by a chain 435 to a sprocket 436 secured on a second countershaft 437 at one end thereof. A pulley 438 is secured on the other end of countershaft 437 and is connected by a belt 439 to a pulley 440 secured on shaft 441 of an electric motor mounted in base frame 39. This motor has associated therewith a controller 443 of known type, at the front of frame 39, there being a connection box 444 at the back of frame 39, as shown in Figure 1C. The driving connections from motor 442 to shaft 427 of the conveyor will readily be understood by reference to Figures 1B, 30A and 31A. The motor drives the conveyor in the manner stated and the conveyor, in turn, drives shaft 267 in the manner previously described.

The channels in the upper run of conveyor 405 receive pipes 445, the forward ends 445a of which are rounded and closed as shown in Figure 1B. Pipes 445 receive steam from a steam pipe 446, through a manifold 447 and tubes 448 connected to this manifold and to the respective pipes 445 adjacent the forward end thereof, as will be clear from Figure 1B. While but one manifold 447 and steam supply pipe is shown, it will be obvious that any suitable number of manifolds and associated steam supply pipes may be provided, as conditions may require, depending upon the length of the pipes 445. A return pipe 450 leads from manifold 447 for return of condensate to the boiler. The pipes 445 extend rearward beyond the conveyor 405, as in Figure 1C, and are connected at their rearward ends to a manifold 451 from which a steam return pipe, not shown, may extend to the boiler. While but one pipe 445 is shown in Figures 1B and 1C, it will be understood that the pipes correspond in number to the channels in the conveyor 405, there being in the machine illustrated by way of example three such channels and, accordingly, three steam pipes 445.

A shaft 455 is rotatably mounted in frame 35a of the forming section of the machine, below the upper run of conveyor 405 and a short distance forward of the pipes 445. A sprocket 456 is secured on shaft 455 (Figures 30A and 31A) and is connected by a chain 457 to a third sprocket 458 secured on countershaft 421. Shaft 455 is thus driven in counterclockwise direction as viewed in Figures 1B and 31A. A pinion 460 (Figures 30A and 31A) is secured on shaft 455 adjacent the other end thereof. Pinion 460 meshes with a pinion 461 secured on a shaft 462 rotatably mounted in a frame 463 (Figure 1B) pivoted at its forward end, at 464, between brackets 465 suitably secured to frame 35a at opposite sides thereof, one of which brackets is shown in Figure 1B. Shaft 462 has secured thereon three forming rolls 466, similar rolls being secured on three additional shafts 467 rotatably mounted in frame 463. A sprocket wheel 469 is secured on shaft 462, similar sprocket wheels 470 being secured on shafts 467, there being a chain 471 about all of the sprocket wheels 469 and 470 in 75

driving engagement therewith. It will be seen that the shafts 462 and 467, and with them the forming rolls 466, are all driven in clockwise direction as viewed in Figures 1B and 31A. Frame 463 is provided, at each side of its rearward end, with an upwardly projecting finger 473 (Figure 1B) connected by a tension spring 474 to the adjacent side of an angle iron member 475 of substantially inverted U-shape. The bight portion 10 of member 475 engages beneath a flange at the top of an angle iron frame 476 suitably secured to frame 35a, and the lower end portions of the arms of member 475 engage in a cross channel element 477 of frame 476. The frame 463 is thus 15 yieldingly held in operative position with pinion 461 in mesh with pinion 460 for driving the forming roll shafts.

In event of jamming of blanks beneath the forming rolls, the frame 463 may swing upward about its pivot in opposition to the tension 20 springs, suitable signal means being provided for indicating such a condition. By withdrawing member 475 from frame 476, the rearward end of frame 463 is released and this frame, together with forming rolls, may be swung upward and forward about its pivot permitting clearly of the jammed blanks with expedition and facility, after which the frame 463 may readily be returned to operative position.

The forming rolls 466 are disposed in sets of four lengthwise of the conveyor 405, each set of rolls being aligned with a channel or groove in the upper run of the conveyor. The blanks b are delivered from the guide means 381, at the 30 rearward end thereof, to the forming rolls, the latter acting to press each blank downward into the channel of the conveyor to conform thereto, this pressing action being progressive due to the inclination of the forward portion of the upper 35 run of the conveyor, previously referred to. As the blank passes beneath the last forming roll 466 it is pressed fully into the channel of the conveyor and is delivered therefrom beneath the steam pipe 445, beneath which it travels in the operation 40 of the conveyor so as to be thoroughly dried before being discharged at the rearward or delivery end of conveyor 405. After being formed in this manner the blank is of arcuate cross section and becomes a trouser guard, such as guard 45 45 g shown in Figure 26. This guard is intended for use with a wire coat hanger h of known type, by being placed over the cross bar i of the hanger, with the end portions of the latter engaged in the 50 slots c of the guard. The guard g presents a rounded surface for supporting a pair of folded trousers placed thereover, thus preventing objectionable transverse creasing of the trousers, and the serrated edges of the guard serve to prevent the trousers from slipping transversely 55 thereof and thus becoming displaced.

The guards thus formed from the blanks are 60 discharged from the rearward end of conveyor 405 onto the upper runs of delivery belts 480 (Figures 1C, 30A and 31A) passing about pulleys 481 and 482 secured on rotatably mounted shafts 483 and 484, respectively. The upper run of each belt travels between the lower portions of two vertical guides, one of which is shown at 485, these guides providing in effect, with the upper run of the belt, a trough having a movable bottom wall. Each of these troughs is aligned with a groove or channel of the conveyor 405 to receive the guards discharged therefrom, the portion of steam pipe 445 extending rearward be-

yond conveyor 405 serving as a guide to direct the guard into the trough.

A pulley 487, secured on shaft 484, is connected by a belt 488 to a pulley 489 secured on shaft 490 of an electric motor 491 suitably mounted on frame 35a above sub frame 39 (Figures 1C, 30A and 31A). The belts 480 are thus driven from motor 491, the drive being such that the upper runs of the belts travel rearward, as indicated in Figure 31A.

The belts 480 are inclined upward and rearward of the machine, as shown in Figure 1C. A hopper structure 494 is supported at the rearward end of frame 35a and is separated by vertical partitions, one of which is shown at 495, into vertical hopper compartments aligned with the troughs in which the upper runs of the belts 480 operate. Each of these vertical compartments receives a bobber 496, which may be formed of sheet metal and preferably is of trough shape in cross section to correspond approximately to the shape of the guards. Bobber 496 is provided with a depending stem 497 pivoted at 498 and 499 to the rearward ends of two links 500 and 501, respectively. Link 501 is pivoted at its forward end, on a rod 502 extending transversely of frame 35a, link 500 being pivoted at its forward end on a rod 503. A counterweight 504 is suitably secured to the forward end of link 500 and serves to counterbalance the bobber and links and associated parts. A rod 505, provided with a turnbuckle 506, connects link 500, at a point a short distance in rear of rod 503, to one arm of an angle lever 507 pivoted at 508 on a cross rod. A weight 509 is attached to the other arm of lever 507. It will be seen that the position of the bobber 496 may be adjusted by manipulating the turnbuckle 506 to increase or decrease the length of rod 505. The bobber 496 normally occupies substantially the position shown in Figure 1C, for receiving guards discharged from the belt 480. The guards, as delivered from the belt 480, are stacked one upon the other and, as the load increases, the bobber 496 gradually moves downward. Operators at the rearward end of the machine remove the stacked guards from the bobber which, upon removal of the guards, is moved upward by the weight 509 and associated parts for reception of a further load of guards.

Referring to the forming rolls 466 and the drive means therefor, it is desirable that shaft 455 be provided with a floating mounting at the end thereof adjacent gear 460. This end of shaft 455 is rotatably supported by a lever 512 (Figure 31a) pivoted at 513 a short distance forward of shaft 455. A tension spring 514 is anchored at its lower end in a suitable manner and has its upper end attached to the forward end of lever 512, for urging upward the rearward portion of this lever, a stop 515 being provided to limit upward movement of the rearward end of lever 512. When the frame 463 carrying the forming rolls 466, is swung downward into operative position, if gear 461 does not mesh with gear 460 the shaft 455 may swing downward slightly until these gears mesh properly, shaft 455 then being held in its normal position. It will be understood, of course, that suitable provision is made for the referred to movements of shaft 455. This means of providing a floating mounting for a shaft is, in general, known and need not be described in greater detail.

The machine so far described is intended for producing trouser guards or like articles from

strip material as a continuous operation, the material in strip form entering the machine at the forward end thereof and the finished guards being discharged at the rearward or delivery end 5 of the machine. It is desirable under certain conditions, as where strip material is not readily available in considerable lengths, to provide means whereby pre-cut blanks may be delivered to the forming section of the machine to be 10 formed thereby into guards or analogous articles. To that end, I have provided a feed hopper in which the blanks may be stacked and delivered therefrom to the forming means, such feed hopper means being interchangeable with the transfer unit 342, thus rendering it possible to use the machine for continuous operation in the manner above described, or for forming pre-cut blanks 15 into guards or analogous articles.

I provide a hopper frame having at each side 20 a side member 520 provided with a flange 521 adapted to seat upon and be bolted to flange 346 of frame 35a, as shown in Figure 27. Side member 520 of this hopper frame conforms in shape and size to the rearward side portion of the frame 25 of transfer unit 342, as will be clear from a comparison of Figures 27 and 1B. By removing unit 342, in the manner previously described, frame 520 may be bolted in place upon frame 35a to replace the transfer unit 342. That renders it 30 possible to substitute the feed hopper unit for the transfer unit with expedition and facility.

The frame of the feed hopper unit comprises angle cross members 522 upon which are mounted angle guide members 523 arranged in pairs, there 35 being three pairs of the guide members 523 in the machine illustrated. Each pair of angle guide members 523 is adjustably secured, adjacent each end, to a base plate 524 which seats upon a cross member 522. The latter is provided 40 with a slot 525 receiving a screw stud 526 secured in base plate 524, this stud receiving a nut 527 and a washer 528, there being a compression coil spring 529 confined between washer 528 and the upper arm of cross member 522. An 45 angle bracket 530 is secured to the under face of base plate 524 and receives the threaded inner end portion of an adjusting rod 531. The rod is rotatably mounted through a suitable support or bracket of the hopper frame and is confined against lengthwise movement. The angle 50 members 523 of each pair may thus be adjusted to accommodate blanks of different widths, within limits, and each pair of angle guide members 523 may be adjusted transversely of the hopper frame, at each end, for accurately adjusting and 55 positioning the pairs of guide members. This arrangement is similar in all essential respects to the construction and operation of the guide means 381 shown in Figures 1B, 21 and 22 and requires no further detailed description. Each 60 of the angle guide members 523 has secured thereto, as by means of a connecting plate 532 and associated screws, two flat upwardly extending arms 533. These arms provide, in conjunction with the angle guide members, hopper 65 means for receiving and supporting a stack of pre-cut blanks.

A shaft 535 is rotatably mounted, adjacent the forward end of guide members 523, in two brackets, one of which is shown at 536 in Figure 27, adjustably secured, as by bolt and slot means 537, to the hopper frame side members 520. Shafts 538, 539, 540 and 541 are rotatably mounted in the feed hopper frame beneath the pairs of guide members 523. Each of the shafts 538, 539,

540 and 541 has secured thereon three rollers 542 which extend upward between the pairs of guide members 523, and shaft 535 has secured thereon three rollers 543 aligned with the rollers 542, it being noted that rollers 543 are higher than the rollers on shaft 538 and that the height of the rollers decreases rearwardly of the feed hopper. The rollers 543 and 542 thus provide a support inclined downward and rearward of the hopper, upon which the stack of blanks may rest.

An angle iron frame 545, of substantially inverted U-shape, has its arms suitably secured to side frame members 520 of the feed hopper unit designated generally 546, frame 545 extending upward above shaft 540. An angle cross bar 547 is suitably secured, as by welding, to the forward flange of frame 545 a short distance from the lower ends of the arms of the latter frame. An upper angle iron frame 548, of substantially U-shape in plan, is secured to the arms of frame 545 and extends rearwardly therefrom. Frame 548 overlies a lower angle iron frame 549 of substantially U-shape in plan secured to the arms of frame 545. The bight portion of frame 548 slidably receives shanks 550 extending upward from forks, one of which is shown at 551, each of which carries a roll 552 cooperating with roll 542 on shaft 541 for gripping the blanks. Roll 552 is yieldingly urged downward by a coil compression spring 553 mounted about shank 552 and confined between frame 549 and fork 551. Fork 551 is extended forward beyond roll 552 and receives a rod 554 suitably secured at each end in a tab 555 extending rearward from the arm of frame 545. The fork 551 is thus restrained against turning movement and held in position with the roll 552 properly aligned with the cooperating roll 542 on shaft 541. It will be understood that there are three rolls 552, one disposed between each pair of angle guide members 523.

A steam separator 556, of suitable known type, is supported by frame 548 and extends rearward therefrom. This separator is provided with an inlet tube or pipe 557 connected by a tube 558 to a suitable valve 559 connected to a nipple 560 suitably secured to manifold 447. The separator 556 is provided with a suitable condensate return line (not shown), in a known manner. A head 561 is connected to separator 556 at the lower end thereof and has attached thereto three tubular arms, one of which is shown at 563. Arm 563 extends downward and rearward from head 561, with its lower portion spaced a slight distance above the horizontal flanges of angle guide members 523, and is closed at its rearward end, this arm being provided in its under face with a plurality of suitably disposed perforations for directing jets of steam against the blanks passing beneath the arm. That provides means for moistening blanks as they pass rearward from the stack feed hopper unit 546.

Three gates, one of which is shown at 565, are mounted for sliding movement on angle cross member 547 and on frame 545. Each of these gates is in the form of a flat comparatively thick metal strip of a width substantially equal to the distance between the vertical flanges of each pair of angle guide members 523, and has its lower end portion tapered in width downward and bent rearward at a slight angle, as at 566. A screw stud 567 is secured to gate 565 a short distance above the lower end thereof and extends through a vertical slot 568 in cross member 547. Stud 567 receives a coil compression spring 570, confined between nut 569 and the vertical flange

of angle cross member 547, this spring holding gate 565 seated against the vertical arm of cross member 547. At its upper end gate 565 has an angle bracket 572 secured to its rearward face, this angle bracket receiving a screw stud 573 suitably secured in the bight portion of frame 545. Adjusting nuts 574 are threaded on stud 573, at the lower and the upper face of the rearwardly extending horizontal arm of bracket 572. Stud 573 and nuts 574 provide means for adjusting gate 565 vertically and securing it in adjustment.

A sprocket 575 is secured on shaft 535 (Figure 29) and is connected by a chain 576 to a sprocket 577 secured upon shaft 538, the latter shaft having a sprocket 578 secured on its other end, the latter sprocket being connected by a chain 579 to a sprocket 580 secured on the corresponding end of shaft 539. A sprocket 581 is secured on the other end of shaft 539 and is connected by a chain 582 to a sprocket 583 secured on the corresponding end of shaft 540, there being a sprocket 584 secured on the other end of shaft 540. Sprocket 584 is connected by a chain 585 to a sprocket 586 secured on the corresponding end of shaft 541. The latter shaft is of greater length than shaft 540, which is of the same length as shafts 539, 528 and 535. A sprocket 587 is secured on the other end of shaft 541 and is connected by a chain 588 to a second sprocket 589 secured on shaft 455 outward beyond sprocket 456. The latter sprocket is connected by chain 457 to sprocket 458 on shaft 421 (Figures 30A and 31A), which is driven from the forward conveyor shaft 460, by means of chain 419 and sprockets 418 and 420, as previously described. When the stack hopper unit 546 is used, sprocket 268 is declutched from shaft 267 thus disabling the first section of the machine in the manner previously described, shaft 267 being then driven idly from shaft 421, by means of chain 423 and sprocket 422 and 424, as has been described above.

The rolls 542 and 543, upon which the blank *b* at the bottom of the stack rests are thus driven in counterclockwise direction, as viewed in Figure 27, the rolls on shafts 539, 540, and 541 are driven at the same speed, the roll on shaft 538 is driven at a somewhat slower speed than the rolls on shafts 539, 540 and 541, and the roll on shaft 535 is driven somewhat slower than the roll on shaft 538. Preferably these rolls are rubber covered, as is roll 552. The angle guide members 523 of each pair are properly adjusted to suit the width of the blanks *b* and the respective pairs of angle member 523 are adjusted, in the manner above described, so as to align the rearward ends of these guide members accurately with the grooves or channels in the upper run of the conveyor 405. Gate 565 is so adjusted that but one blank can pass between the lower edge thereof and the roll 542 on shaft 540. In the rotation of the rolls 542 and 543 the blanks are fed one at a time from the bottom of the stack beneath gate 565 and to the pair of gripping rolls comprising roll 552 and the roll on shaft 541. These gripping rolls pull the blanks from beneath the stack and feed them beneath the arms 563, where they are moistened in the manner described, and then to the forming rolls 466. The latter rolls force the blanks into the channels in the conveyor and the blanks then move rearward beneath the steam pipes 445, being delivered as finished guards at the rearward end of the forming unit or section of the machine, in the manner previously described.

When the stack feed hopper 546 is removed and replaced by the transfer unit 342, tube 558 is disconnected from valve 559 and may be replaced by a pressure gauge or, if desired, valve 559 may be closed.

The slitting and cutting mechanism disclosed but not claimed, per se, herein, constitutes the subject-matter of my copending application, Serial No. 411,522, filed September 19, 1941, which is a division of my instant application.

In practice a suitable housing, which need not be described in any detail, is provided for enclosing the frame work and the various mechanisms of the machine. It will be understood that changes in construction and arrangement of parts of my invention may be resorted to without departing from the field and scope thereof, and I intend to include all such variations, as fall within the scope of the appended claims, in this application in which the preferred forms only of my machine have been disclosed.

I claim:

1. In a machine of the character described, a printing unit, means for optionally enabling and disabling said unit, slitting rolls, and means for alternatively feeding strip material to said slitting rolls only and to said printing unit and thence to said slitting rolls.

2. In a machine of the character described, a printing unit, means for optionally enabling and disabling said unit, slitting rolls, entrance and guide means for directing strip material to said printing unit, entrance and guide means for directing strip material to said slitting rolls, and guide members for directing strip material from said printing unit, one of said guide members being in advance of said slitting rolls for delivering the strip thereto.

3. In a machine of the character described, a printing unit adjacent the front of said machine, means for optionally enabling and disabling said unit, slitting rolls adjacent the front of said machine above said unit, a guide roll in back of said printing unit, and a second guide roll in front of said slitting rolls with its top substantially in the cutting plane of said slitting rolls, said guide rolls cooperating to guide the strip from said printing unit to said slitting rolls, said machine having at its front two entrance openings for respectively delivering strip material directly to said printing unit and directly to said slitting rolls.

4. In a machine of the character described, a printing unit adjacent the front of said machine, means for optionally enabling and disabling said unit, slitting rolls adjacent the front of said machine above said unit, a guide roll in back of said printing unit, a second guide roll in front of said slitting rolls, and guides between said slitting rolls and said second guide roll, the latter being disposed to deliver the strip to said guides, said guide rolls cooperating to guide the strip from said printing unit to the guides of said slitting rolls, said machine being open at its front for introduction of strip material to either the printing unit or the slitting rolls, optionally.

5. In a machine of the character described, a printing unit, slitting rolls, guide means for guiding strip material to said slitting rolls, guide means for guiding strip material from said printing unit to said slitting rolls guide means, measuring rolls for gripping the strip and moving it through said guide means and said slitting rolls, common drive means for said printing unit and said measuring rolls, means for deliv-

ering strip material alternatively to said printing unit and to said slitting roll guide means only, and means for optionally disabling said printing unit independently of the drive for said measuring rolls.

6. In a machine of the character described, a printing unit, slitting rolls, guide means for guiding strip material to said slitting rolls, guide means for guiding strip material from said printing unit to said slitting rolls guide means, both of said guide means comprising guide members adjustable to accommodate different widths of strip, measuring rolls for gripping the strip and moving it through said guide means and said slitting rolls, common drive means for said printing unit and said measuring rolls, means for delivering strip material alternatively to said printing unit and to said slitting roll guide means only, and means for optionally disabling said printing unit independently of the drive for said measuring rolls.

7. In a machine of the character described, a slitting and cutting section for slitting strip material and cutting it into blanks, a forming section comprising a conveyor and cooperating rolls for shaping the blanks to desired form, means driving said conveyor, a shaft driven from said conveyor and having driving connection to said rolls, means for driving said first section from said conveyor comprising means for optionally stopping operation of said first section while permitting continued operation of said conveyor and shaft, a removable transfer unit between said sections for transferring cut blanks from said first section to said forming rolls and conveyor of said second section, a driven feed unit for feeding blanks to said forming rolls adapted to be mounted in replacement of said transfer unit, and means for establishing driving connections between said feed unit and said shaft.

8. In a machine of the character described, a slitting and cutting section for slitting strip material and cutting it into blanks, a forming section comprising a conveyor and cooperating rolls for shaping the blanks to desired form, means driving said conveyor, a shaft driven from said conveyor and having driving connection to said rolls, means for driving said first section from said conveyor comprising means for optionally stopping operation of said first section while permitting continued operation of said conveyor and shaft, a removable transfer unit between said sections for transferring cut blanks from said first section to said forming rolls and conveyor of said second section, a driven feed hopper unit for feeding blanks from stacks to said forming rolls adapted to be mounted in replacement of said transfer unit, and means for establishing driving connections between said feed hopper unit and said shaft.

9. In a machine of the character described, means for slitting to desired width strip material of a width equal to a multiple of the desired width thereby producing from the original strip a plurality of strips of desired width, said slitting means being adjustable to accommodate different widths of original strip and to slit the latter into strips of different desired widths, guide means for directing the original strip to said slitting means adjustable to accommodate different widths of original strip, means for cutting the strips into blanks of desired length, means for directing and delivering to said cutting means strips from said slitting means comprising guide means adjustable to accommodate strips of dif-

ferent widths, means for forming the blanks to desired shape, and means for directing and delivering the blanks from said cutting means to said forming means comprising guide means adjustable to accommodate blanks of different widths.

10. In a machine of the character described, two aligned sets of slitting rolls, each set comprising a pair of upper rolls and a pair of lower rolls respectively cooperating with said upper rolls, means supporting the rolls of the respective pairs for relative adjustment toward and away from each other and one pair of rolls of a set for adjustment toward and away from the other pair of rolls of that set into and out of cooperating relation thereto, means for delivering a strip of material to said slitting rolls comprising guide means adjustable to accommodate different widths of strip, cutting means for cutting into blanks of desired length strips from said slitting rolls, means for delivering strips from said slitting rolls to said cutting means comprising guide means adjustable to accommodate strips of different widths, means for forming the blanks to desired shape, and means for delivering the blanks from said cutting means to said forming means.

11. In a machine of the character described, two aligned sets of slitting rolls, each set comprising a pair of upper rolls and a pair of lower rolls respectively cooperating with said upper rolls, means supporting said upper rolls for adjustment toward and away from each other and

toward and away from said lower rolls into and out of cooperating relation thereto, means for delivering a strip of material to said slitting rolls comprising guide means adjustable to accommodate different widths of strip, cutting means for cutting into blanks of desired length strips from said slitting rolls, means for delivering strips from said slitting rolls to said cutting means comprising guide means adjustable to accommodate strips of different widths, means for forming the blanks to desired shape, and means for delivering the blanks from said cutting means to said forming means.

12. In a machine of the character described, two aligned sets of slitting rolls, each set comprising a pair of upper rolls and a pair of lower rolls respectively cooperating with said upper rolls, means supporting said upper rolls for adjustment toward and away from each other and toward and away from said lower rolls into and out of cooperating relation thereto, means for delivering a strip of material to said slitting rolls comprising guide means adjustable to accommodate different widths of strips, cutting means for cutting into blanks of desired length strips from said slitting rolls, means for separating strips from said slitting rolls and delivering them to said cutting means comprising guide means adjustable to accommodate different widths of strip, means for forming the blanks to desired shape, and means for delivering the blanks from said cutting means to said forming means.

LAWRENCE A. MOORE.
